UNITED STATES PATENT OFFICE.

WILLIAM A. LURIE, OF CHICAGO, ILLINOIS.

DOOR-LOCK.

1,168,524.

Specification of Letters Patent. Patented Jan. 18, 1916.

Application filed June 17, 1914. Serial No. 845,620.

To all whom it may concern:

Be it known that I, WILLIAM A. LURIE, a citizen of the United States, residing at Chicago, county of Cook, and State of Illinois, have invented a new and useful Improvement in Door-Locks, of which the following is a specification.

My invention relates to door locks and its main object is to provide improved mechanism within the door jamb for coöperating with the locking bolt mounted in the door in order that the bolt may be readily withdrawn upon actuation of a knob or key while at the same time the lock can not be picked.

Another object is to provide an additional locking mechanism in the form of a latch bar controlled automatically to span between the door and jamb when the door is closed.

Another object is to greatly simplify the construction and arrangement of the various locking and inter-locking parts.

The various features of the invention are clearly illustrated on the accompanying drawings in which:

Figure 1 is a front elevational view of the door and jamb parts of the lock with the inclosing plate removed; Fig. 2 is a sectional view on plane 2—2, Fig. 1; Fig. 3 is a view similar to Fig. 1 but showing the bolt withdrawn from the jamb; Fig. 4 is a sectional view on plane 4—4, Fig. 3; Fig. 5 is a sectional view on plane 5—5, Fig. 1; Fig. 6 is a sectional view on plane 6—6, Fig. 1; Fig. 7 is a sectional view on plane 7—7, Fig. 3, and Fig. 8 is a sectional view on plane 8—8, Fig. 3.

The mechanism for the lock section to be inserted in a door is inclosed in a casing 10 having the escutcheon plate 11 provided with the bolt opening 12. The bolt plate 13 carries the head 14 having the tapered outer surface 15, the bolt being adapted to travel longitudinally and being guided by its tail 13 passing through the opening 16 in the inner wall of the inclosing frame, a spring 17 encircling the tail tending to hold the bolt in outer position. The bolt head is hollow and contains pawls 18 and 19 pivoted at the inner ends of their bases 20 and 21 on pins 22 and 23 respectively which extend from the head as clearly shown in Fig. 8. The outer ends of the pawls are offset from their bases and have inner and outer teeth *a*, *b*, and *a'*, *b'*, respectively, the

teeth *a*, *b* being adapted to pass through passageways *c* and *d* and the teeth *a'*, *b'* being adapted to pass through passageways *c'* and *d'* to the exterior of the head to project beyond the lower sides thereof. The cross walls 24 and 24' limit the outward swing of the pawls as clearly shown in Fig. 1.

On the bolt plate 13 is a bar 25 which has a spline 26 extending from its inner face into a groove 27 cut in the bolt plate, the spline end 26' projecting a distance beyond the outer end of the bar 25 and between the bases of the pawls. The opposed faces of the pawl bases are curved to form cam surfaces *e* and *e'* with which the outer edges of the bar 25 coöperate. A spring 28 connects between the pawls and tends to swing them into the bolt head. When the bar 25 is out, as shown in Fig. 1, the pawls will be spread apart by the engagement of the bar with the cam surfaces *e* and *e'* and the teeth *a*, *b* and *a'*, *b'* will project beyond the upper edges of the bolt head. However, when the bar 25 is shifted inwardly and its end released from the cam surfaces, the spring 28 will swing the pawls inwardly to be entirely within the bolt head, as shown in Fig. 3.

Shifting of the bar 25 to release the pawls may be accomplished in a number of ways. The usual way is by means of door knob mechanism of which the shaft section 29 is shown, this shaft section carrying a hub 30 from which extends the arm 31 having the wing 32 at its end extending at right angles to the arm and parallel with the shaft section 29. This wing extends through the notches 33 and 34 cut in the lower edges of the transverse enlargements 35 and 36 of the bolt plate and bar 25 respectively. The hub 30 has the abutment arm 37 at its lower end engaged by a spring 38 secured to the lock inclosing housing 10, and this spring 38 tends to hold the arm 31 in vertical position, as shown in Fig. 1. The shaft section 29 extends to the inside of the door and is provided with the usual knob (not shown). When this knob is turned in clockwise direction from the inside of the door the arm 31 is swung and the wing 32 effects shifting of the bolt and bar 25. However, on account of the notch 34 in bar 25 being set in advance of the notch 33 of the bolt plate 116 the bar 25 will be shifted first in order to release its outer end from the pawls to allow

these pawls to be swung into the bolt head. It is only after the pawls have been thus released and drawn into the bolt head that the wing 32 engages with the rear edge of the notch 33 and shifts the bolt structure inwardly. In Fig. 3 the inner positions of the bolt and cam plate are clearly shown. Upon release of the knob the spring 38 will swing the arm 31 back to its vertical position (Fig. 1), the spring 17 forcing the bolt plate forwardly until it abuts against the stops 39 extending from the frame 10, the spring 40 then pulling the bar 25 forwardly until the rear edge of notch 34 reaches the wing 32, the pawls 18 and 19 being then again forced outwardly with their inner teeth b and b' projected in front of the escutcheon plate 11.

Key mechanism could also be used to draw in the bolt and K represents the cylinder of a cylinder lock. The enlargements 35 and 36 of the bolt plate 13 and bar 25 have notches 33' and 34', respectively in their upper edges and arms controlled by the cylinder lock mechanism may be provided for controlling the locking plate and bar in the same manner as these elements are controlled by the wing 32 extending from the door knob shaft. Such cylinder lock controlled mechanism is not shown as it does not form part of this invention.

When the bolt is shifted outwardly the pawls will be automatically spread and their inner teeth b and b' carried in front of the escutcheon plate 11 and the bolt cannot be shifted in until the pawls are drawn into the bolt head. This, however, can be effected only by the turning of the knob or by the turning of the key. If such pawls are not provided a knife blade or similar implement can be inserted between the escutcheon plate 11 and the door jamb and the bolt can be slid inwardly and the door opened. The pawls will, however, prevent this. It is, however, common practice to close a door by slamming it and it is therefore necessary that provision be made to withdraw the pawls to allow inward shift of the bolt when its head strikes the door jamb. A trigger 40' is therefore provided and pivoted in the bolt head at its inner end with its head h normally extending beyond the beveled surface 15 of the bolt head. The trigger is pivoted in the plane of the end 26' of the bar 25 and the shape of the head h is such that when it encounters the jamb in advance of the bolt head surface 15 when the door is slammed its inner end will strike the end 26' to effect shifting inwardly of bar 25 and release of the pawls in order that the pawls may be withdrawn into the bolt head before the surface 15 strikes the door jamb. Any suitable spring 41 is provided for holding the trigger in its outer position.

35 Provision is preferably made to lock the

bolt against shifting from the outside of the door. As best shown in Figs. 5 and 6, the outer knob shaft section 29' is connected with the inner knob shaft section 29 in the usual manner by a threaded stud 42. The shaft 29' carries a hub 43 from which extends the arm 44 in the path of which extends the wing 32 extending from arm 31 controlled by the knob shaft section 29. A spring 45 engaging the arm 46 on hub 43 tends to hold arm 44 in vertical position. The hub 43 from which arm 31 extends has also a locking arm 47 extending therefrom. On the stud 48 extending from the lower wall of the inclosing frame 10 is pivoted the locking plate 49 whose outer end has pin and slot connection with lever 50 to be swung to carry its inner end above locking arm 47 when the arm 44 is in normal position (see Figs. 1 and 3). When the arm 47 is thus blocked by the locking plate 49 it will be impossible to turn the outer knob shaft section 29'. The shaft section 29 is, however, free at all times to be turned by its knob in either direction. When the plate 49 is swung to release the arm 47 the lock can be operated from either inside or outside by turning the respective knob. The lever 50 is pivoted on a stud 51 and at opposite sides of the stud carries buttons 52 and 53 which project through the front wall 10' of the lock housing. When the upper button is pushed in the locking plate 49 will be swung to release the locking arm 47 and when the lower button is pushed in the plate 49 will be swung into position above the locking arm 47, the buttons being accessible only from the inside of the door.

Describing now the construction of the jamb section of the lock, the mechanism therefor is inclosed in a housing 54 having the escutcheon plate 55. This escutcheon plate is provided with an inlet opening 56 which registers with the lock bolt opening 12 when the door is closed. Normally closing the opening 56 is a plate 57 carried at the front of a vertical bar 58 which is slideable at its upper and lower ends on rods 59 and 60 which rods may be in the form of screws for holding the housing 54 together. Springs 61 and 62 mounted on the respective rods tend to hold the bar 58 in forward position with the plate 57 within the opening 56. In front of the bar 58 upper and lower latch plates 63 and 64 are vertically slideable in guides 65 and 66 secured to the opposite sides of the housing 54. The latch plates at their ends are slideable on and guided by the rods 67 and 68, springs 69 and 70 encircling these rods between the latch plates and tending to hold the latch plates apart. Pivoted on a rod 71 above the latch plate 63 is a cam plate 72 whose outer end is above the latch bar 63. On a rod 73 is pivoted the lower cam plate 74 whose outer

end is below the latch plate 64. The cam plates 72 and 74 have respectively the longitudinal cam slots 75 and 76 into which extend pins 77 and 78 on the bar 58 the cam slots being in such direction that when the bar 58 is shifted rearwardly the cam plates will be swung toward each other to bring their outer ends against the latch plates 63 and 64 to force them together. The plate 58 has notches 79 and 80 for receiving the latch plates 63 and 64 when the bar is in its outer position (see Fig. 3).

With the above arrangement when the door is being closed the bolt on the door is forced inwardly until the bolt opening 12 comes into register with the jamb opening 56, and then the bolt encounters the plate 57 and this plate together with bar 58 is forced into the jamb lock section. Upon such inward movement of the bar 58 the cam plates 72 and 74 are swung toward each other to force the latch plates 63 and 64 together and against the upper and lower surfaces of the bolt head. Then when the pawls in the bolt head are swung outwardly the outer teeth a and a' will be behind the latch plates 63 and 64 and inward movement of the bolt will be blocked unless the bolt pawls are first drawn in. As before described, the inner pawl teeth b and b' are blocked by the escutcheon plate 11 when the pawls are extended. All the parts move in proper timed relation. When the lock is drawn in by means of a door knob the bolt pawls are not swung out until the knob has been released after the door has been closed. If the door is slammed the trigger will, upon striking the jamb, draw the pawls inwardly and the beveled surface 15 of the bolt head striking the jamb will then force the bolt inwardly, and the bolt pawls will not again be swung out until the bolt head has entered the jamb lock section. After the bolt head enters the jamb lock section the latch plates 63 and 64 will be in front of the outer teeth b , b' of the pawls. Both the inner and outer pawl teeth of the bolt being thus blocked it is impossible, except by breaking the door and jamb, to unlock the door unless the pawls are withdrawn either by actuating a knob or a key.

I also provide additional locking mechanism automatically controlled by the main locking mechanism. A latch bar 81 is pivoted on a shaft 82 journaled in the outer and inner walls of the jamb lock housing 54, the latch bar being at the outside of the housing 54 as clearly shown in Fig. 4. The end of the bar carries the counter weight 83 which tends to hold the bar in vertical position. Pivoted on a stud 84 is a lever 85 whose upper end has pin and slot connection with the crank arm 86 extending from the shaft 82. The lower end of the lever has the slot 87 receiving the pin 88 extending from the

bar 58, the arrangement being such that when the bar 58 is forced inwardly to effect interlock of the latch plates and bolt pawls the lever 85 will be swung to effect rotation of shaft 82 to cause the latch bar 81 to be swung to horizontal position with its end in front of the housing 10 of the door lock section (see Fig. 2). The latch bar then prevents opening of the door, and in order to prevent forcible removal of the bar 75 I provide a locking detent therefor, this detent being in the form of an L-shaped member 89 arranged within the housing 10 and pivoted at its lower end to ears 90 extending from the housing, the detent end g extending through the opening 91 above the latch bar 81 when the latch bar is in closed position. As shown in Fig. 5, a spring 92 tends to swing the detent member 89 into the housing but during locking conditions this 85 is prevented by a locking plate 93 which is pivoted on the ledge 94 and extends forwardly with its end behind the detent 89 (see Fig. 2). In order to withdraw the detent 89 to allow swinging of the bar 81 to 90 locking position, a link 95 connects between the locking bolt 13 and the locking plate 93 in order that when the bolt is withdrawn preparatory to its entrance into the jamb lock mechanism, the locking plate 93 will be 95 released from the detent 89 and this detent swung inwardly by its spring out of the path of the latch bar 81. Then when the bolt is released after locking of the door and moves outwardly the detent plate 93 will be 100 swung outwardly to carry its cam surface 93' against the detent 89 to move this detent outwardly to project its end g over the latch-bar 81 to thus lock the latch bar. If the door is now to be opened the bolt is withdrawn either by means of a knob or key and this effects withdrawal of the cam plate 93 from the detent 89 which swings inwardly to release the latch bar 81, this bar swinging back to normal position as the lever 85 is 110 swung by the bar 58 when this bar is shifted back to its normal position. The lock housings 10 and 54 are preferably set into the door and jamb respectively to be entirely surrounded with only the escutcheon plates 115 visible. The latch bar 81 and its detent 89 will then be protected by a layer of wood or metal and access thereto will be practically impossible except by breaking away the wood or metal.

I thus produce a lock comprising parts simple in construction and arrangement, the parts being in greater part adapted to be stamped from sheet metal and being therefore very strong and durable. Although the 125 bolt can be readily withdrawn at any time by means of a door knob or key, it will be impossible to insert a knife blade or other implement between the door and jamb to withdraw the bolt as the bolt is locked 130

against retraction by two sets of teeth which are fully protected against access from the outside. The latch bar which is automatically swung in front of the door affords additional protection and such bar can not be unlocked except by turning of the knob or by the use of a key.

I do not, of course, desire to be limited to the exact details of construction, arrangement and operation shown, as changes and modifications are no doubt possible which would still come within the scope of the invention as defined by the claims, and I claim as follows:

1. In a lock, the combination of a bolt plate having a head, pawls pivoted in said head and having inner and outer teeth adapted to project beyond the opposite sides of the head, a bar movable on said bolt plate tending to keep said pawls spread apart with the teeth projecting, opposed latch plates in the jamb with which the door is associated, means controlled by entry of the bolt into the jamb for causing said latch plates to be moved against the opposite sides of said bolt head and in front of the outer teeth of the pawls when said teeth are projected from the head, an escutcheon plate on the door having an opening through which the bolt head travels and disposed in front of the inner teeth of the pawls when such teeth are projected, and actuating means associated with said bolt plate and bar thereon and adapted to first cause shifting of said bar to release the pawls and then inward movement of said bolt plate.

2. In locking mechanism for doors, the combination of a door lock section comprising an escutcheon plate having a bolt opening, a bolt plate having a head adapted to slide through said opening, pawls pivoted in said head and having teeth, means tending to swing said pawls to be entirely within said head, a barslidable on said bolt plate and normally engaging said pawls to spread them apart to cause their teeth to project beyond the sides of the bolt head and in front of the escutcheon plate whereby said bolt plate is prevented from inward movement by pressure thereon, a door knob shaft and a hub thereon, an arm extending from said hub, said bolt plate and bar thereon having notches in which the end of said arm engages, said notches being offset whereby upon turning of said knob shaft and swinging of said arm said bar will be shifted a distance first to release the pawls to allow said bolt plate to be then shifted inwardly, an abutment arm extending from said hub, and a locking plate adapted to be set with reference to said abutment arm to prevent turning of said knob shaft and shifting of the bolt.

3. In locking mechanism for doors, the combination of a door lock section compris-

ing an escutcheon plate having a bolt opening, a bolt plate having a head adapted to slide through said opening, pawls pivoted in said head and having teeth, means tending to swing said pawls to be entirely within said head, a barslidable on said bolt plate and normally engaging said pawls to spread them apart to cause their teeth to project beyond the sides of the bolt head and in front of the escutcheon plate whereby said bolt plate is prevented from inward movement by pressure thereon, a door knob shaft and a hub thereon, an arm extending from said hub, said bolt plate and bar thereon having notches in which the end of said arm engages, said notches being offset whereby upon turning of said knob shaft and swing of said arm said bar will be shifted a distance first to release the pawls to allow said bolt plate to be then shifted inwardly, an abutment arm extending from said hub, a pivoted locking plate, and an abutment controlled lever connected with said locking plate for setting said plate in the path of said abutment arm to prevent rotation of the knob shaft.

4. In locking mechanism for doors, the combination with a lock housing secured to the door, a lock bolt reciprocable in said housing and having a head, and means for controlling the shifting of said bolt, of a lock housing secured in the jamb of the door frame, a latch bar pivoted on said jamb housing and adapted to be swung to position in front of the door to lock the door against opening, means within said jamb housing controlled by the entry of the bolt head thereinto for effecting swinging of said latch bar to locking position, and a detent for locking the latch bar in locking position.

5. In locking mechanism for doors, the combination with a housing secured to the door, a bolt slidable in said housing, and means for actuating said bolt, of a housing secured in the jamb of the door frame, a latch bar pivoted to said jamb housing adapted to be swung to engage in front of the door housing to lock the door against opening, actuating lever mechanism within said jamb housing connected with said latch bar to be engaged and actuated by the bolt when said bolt is shifted into the jamb housing, and a detent for locking the latch bar in locking position.

6. In locking mechanism for doors, the combination with a lock housing secured to the door, a lock bolt reciprocable in said housing and having a head, means for controlling the shifting of said bolt, of a lock housing secured in the jamb of the door frame, a latch bar pivoted on said jamb housing and adapted to be swung to position in front of the door to lock the door against opening, means within said jamb

- housing controlled by the entry of the bolt head into said housing for effecting swing of the latch bar to locking position, a detent pivoted on the door housing, and a connection between said detent and bolt adapted upon outward movement of said bolt into the jamb housing to project said detent into the path of said latch bar to lock said latch bar in latch position.

7. In locking mechanism for doors, the combination with a lock housing secured to the door, a lock bolt reciprocable in said housing and having a head, means for controlling the shifting of said bolt, of a lock housing secured in the jamb of the door frame, a latch bar pivoted on said jamb housing and adapted to be swung to position in front of the door to lock the door against opening, means within said jamb housing controlled by the entry of the bolt head into said housing for effecting swinging of the latch bar to locking position, a locking detent for the latch bar pivoted to the door housing, means for holding said detent out of the path of said latch bar when said door is closed and said bolt is within the door housing, and a locking plate for said detent controlled by the movement of said bolt to outer position to first shift said detent into the path of unlatching movement of said latch bar and then to lock such detent in such latch bar locking position.

8. In locking mechanism for doors, the combination with a lock housing secured to the door and having a bolt opening, a bolt slideable in said housing and having a head adapted to be projected through said opening, pawls pivoted on said head, said head having outlets through which the pawl ends may extend beyond the head sides, means for holding the pawls within the head when the bolt is drawn inwardly, means for causing swing of said pawls to project their ends through and beyond said opening when the bolt is shifted outwardly, of a jamb lock housing secured in the jamb of the door frame and having an inlet opening for the bolt head, latch plates at the opposite sides of the jamb housing opening, a bar extending across the opening in the jamb housing in the path of said bolt head to be shifted inwardly as said head passes into said jamb housing, and lever mechanism connecting between said bar and said latch plates for bringing said latch plates together against the opposite sides of said bolt head and behind the projected pawl ends to thereby lock said bolt against withdrawal from the jamb, means mounted in the door lock housing for first releasing the pawls from said latch plates and for then withdrawing the bolt to allow opening of the door, a latch bar pivoted to the jamb housing and adapted to be swung into position in front of the door housing to prevent opening of the door, and lever mechanism connecting between said latch bar and the latch plate actuating bar and adapted to swing said latch bar to locking position simultaneously with the actuation of the latch plates into locking position behind the projecting pawl ends.

In testimony whereof, I have signed my name to this specification in the presence of two subscribing witnesses this 2nd day of June, A. D. 1914.

WILLIAM A. LURIE.
